CLAIM

The ornamental design for a support for signal flags or
the like, as shown and described.

DESCRIPTION

FIG. 1 is a perspective view of a support for signal flags or
the like showing my new design, with one end frag-
mentarily broken away to indicate indeterminate
length;

FIG. 2 is a side elevational view, with the opposite side
being a mirror image thereof;

FIG. 3 is a front elevational view, with both ends frag-
mentarily broken away to indicate indeterminate
length;

FIG. 4 is a rear elevational view thereof, as shown in
FIG. 3.
